AUTOMOBILE INSTRUMENT PANEL

Antoine Brueyer, Paris, France, assignor to Societe Anonyme Andre Citroen, Paris, France, a corporation of France

Application March 19, 1956, Serial No. 40,662

Claims priority, application France September 22, 1955

Term of patent 14 years

(Cl. D14—6)

Fig. 3

Fig. 1 is a perspective view of an automobile instrument panel, showing my new design.

Fig. 2 is a diagrammatic view showing the configuration at line 2—2 of Fig. 1.

Fig. 3 is an enlarged fragmentary perspective view of the corner of the instrument panel taken on line 3—3 of Fig. 1 showing the instrument cowling.

I claim:

The ornamental design for an automobile instrument panel, substantially as shown.
